UNITED STATES PATENT OFFICE.

EDWIN WATERS, OF ELGIN, ILLINOIS.

INDICATOR.

1,070,563.

Specification of Letters Patent. Patented Aug. 19, 1913.

Application filed March 26, 1913. Serial No. 755,650.

To all whom it may concern:

Be it known that I, EDWIN WATERS, a citizen of the United States, residing at Elgin, in the county of Kane and State of Illinois, have invented certain new and useful Improvements in Indicators, of which the following is a specification.

The indicator which is the subject of the present invention is designed to be used on automobiles or other vehicles for the purpose of indicating the direction the driver is going to turn, and the object of the invention is to provide an indicator of this kind which will be plainly visible in the day time as well as at night, and which can be readily set by the driver. These objects are attained by means of a novel combination and arrangement of parts to be herein-after described and claimed.

In the accompanying drawing forming a part of this specification, Figure 1 is an elevation of an automobile equipped with my improved indicator. Fig. 2 is a sectional view of the lamp provided with the indicator. Fig. 3 is a front elevation of the lamp with the indicator shown in cross section. Fig. 4 is a plan view of the gearing for operating the lamp.

Referring specifically to the drawing, 5 30 denotes the automobile or other vehicle to which the invention is applied. The indicator is an arrow, a hand or other pointer arranged horizontally and adapted to be swung about a vertical axis to indicate horizontal direction. The pointer is a metal frame 6 defining its outline and glazed on both sides, the glass 7 being suitably secured in the frame. Thus a hollow glass pointer is had, the purpose of which structure will 40 be presently described.

The pointer is carried by a lamp of ordinary construction having a rectangular casing 8. One of the faces of the lamp casing carries a white glass 9, and the opposite face 45 has a green glass 10. The two other opposite faces are provided with red glasses 11. This color arrangement may be varied according to the traffic regulation which may be in force in the city or other place where 50 the vehicle is in use. The pointer is carried by the lamp casing 8 at the top thereof and

projects from opposite sides, in which latter are openings. The pointer is in two sections, one of which enters the lamp casing through one of the openings, and the other section 55 through the opening in the opposite side. A strip 12 secured to the top of the lamp casing and extending across the same, has spring fingers 13 at its ends which grip the respective sections of the pointer. Thus, the 60 pointer is securely fastened to the lamp casing. An oil, gas or electric lamp may be employed as the illuminant.

In the base of the lamp casing 8 is a socket into which extends the upper end of a vertical shaft 14, and by means of a set screw 14^a, the lamp casing is made fast to the shaft. A bearing stand 15 supports the shaft, said stand being mounted on any convenient portion of the vehicle body to locate 70 the lamp at the desired place on the vehicle. On the shaft 14 is fast a pinion 16 which is in mesh with a gear 17 having a lever arm 18, which is connected by a link 19 to a hand lever 20 fulcrumed to a stand 21 mounted 75 on the vehicle body, so that the hand lever is within easy reach of the driver. The hand lever has a suitable lock 22. The shaft 14 is tubular so that the current wires for an electric lamp may be run therethrough, if 80 the casing 8 is to be provided with such a lamp.

The device herein described will be mounted in front of the vehicle to indicate to drivers of approaching vehicles, pedestrians 85 and others, the direction the driver intends to turn the vehicle, the pointer being set by means of the hand lever 20 to indicate the direction. Upon operating the hand lever, the lamp casing 8 is rotated and as the 90 pointer is carried by said casing, it swings around therewith. The device may also be mounted at the rear end of the vehicle, so that the driver of a vehicle behind may be 95 notified the course the vehicle in front is going to take.

As the pointer is hollow and made of glass, it will be brilliantly illuminated at night by the lamp, and it is thus rendered plainly visible. In order to enhance the 100 effect, red glass may be employed in the structure of the pointer.

I claim:

An indicator comprising a rotatable lamp, a pointer projecting from the lamp, and a strip secured to the lamp and having spring fingers engaging the pointer to hold the same.

In testimony whereof I affix my signature in presence of two witnesses.

EDWIN WATERS.
